INVENTOR.
Frank W. Aiken,
BY Honora J. Smith,
ATTORNEY.

UNITED STATES PATENT OFFICE.

FRANK W. AIKEN, OF DAYTON, OHIO, ASSIGNOR OF ONE-HALF TO JACOB MILTON RICE, OF DAYTON, OHIO.

COMBINATION BLOTTER AND PENCIL-SHARPENER.

1,363,546.

Specification of Letters Patent. Patented Dec. 28, 1920.

Application filed October 21, 1919. Serial No. 332,283.

To all whom it may concern:

Be it known that I, FRANK W. AIKEN, a citizen of the United States, residing at Dayton, in the county of Montgomery and State 5 of Ohio, have invented certain new and useful Improvements in Combination Blotters and Pencil-Sharpener, of which the following is a specification.

The principal object of the invention is 10 to provide an advertising medium that is not only efficient as such but which is extremely useful as a combined blotter and pencil sharpener. Being a blotter containing a sandpaper or like insert, it is an article 15 which can be cheaply produced in large quantities for a wide distribution among an advertiser's prospective customers.

Since the sandpaper insert is light and flush with the upper surface of the blotter, 20 the latter can be readily mailed at small cost to persons whom an advertiser desires to reach. The device lends itself well to advertising purposes, for on its top surface attractive legends can be placed, suggesting 25 its use as a blotter, and, in addition, pointing out that on its sandpaper insert, pencils may be sharpened without the inconvenience of using a knife for this purpose.

Referring to the accompanying drawings, 30 Figure 1 is a top plan view of one of my improved blotters containing in its upper right hand corner a sandpaper insert covered by a flexible flap. Fig. 2 is a perspective view of said blotter, showing the flap in its raised position to permit a pencil point to be rubbed upon the surface of the sandpaper. Fig. 3 is a longitudinal edge view of said blotter. And Fig. 4 is a top plan 40 view of a square blotter containing a sandpaper insert in its upper left hand corner.

Throughout the specification and drawings, similar reference characters denote corresponding parts.

Referring to the accompanying drawings, 45 the numeral 1 designates an ordinary blotter in whose upper surface is impressed, or otherwise secured, a sandpaper or like insert 2 preferably of disk shape, and approximately flush with the top surface of the blotter. This insert is placed on the blotter to permit pencil points to be sharpened upon it without the necessity upon the part of the user, of resorting to the use of a knife 50 for this purpose. As a time-saver, this

pencil-sharpening insert has everything in its favor, for much more time is required to withdraw a knife from the pocket and open it, than merely to scratch the point of the pencil upon its sandy or rough surface. 60

To prevent the fingers from being soiled by touching the insert after it has been used one or more times, there is secured to the blotter, in a position to cover the insert when not being used, a flexible flap 3. When 65 it is desired to sharpen a pencil, this flap or cover can be easily raised to permit the pencil point to be rubbed upon the sandpaper insert 2 below.

In Fig. 1 the blotter contains a legend 70 which suggests its uses, and, in addition, continuously and effectively calls the attention of the user to the name, address and service of the advertiser. It is thus seen that the blotter lends itself well to effective, and yet relatively inexpensive, advertising. 75

The blotter may be made of any suitable material and in any size. In Fig. 4 is shown a square blotter 4 that contains a 80 sandpaper insert 2 in its upper left hand corner. This blotter 4 is adapted to be folded upon itself along a diagonal 5, so that it may be conveniently slipped under one corner edge of a desk-blotter holder. 85

The insert 2 may likewise be made of any suitable material, and placed at any point in the blotter's upper surface.

Having described my invention, I claim:

1. In a device of the type described, the 90 combination with a blotter, of a pencil-sharpening insert impressed in the upper surface of said blotter a sufficient distance to make the top surface of the insert approximately flush with the top surface of 95 any portion of the blotter, and not projecting below its lower surface.

2. In a device of the type described, the combination with a blotter, of a relatively flat sandpaper insert impressed in its top 100 surface a sufficient distance to make the top surface of the insert approximately flush with the top surface of any portion of the blotter, for the purpose specified.

In testimony whereof I have hereunto set 105 my hand this 20th day of October, 1919.

FRANK W. AIKEN.

Witness:

HOWARD S. SMITH.
